UNITED STATES PATENT OFFICE.

CHARLES W. WRIGHT, OF TOPEKA, KANSAS.

STREET AND STATION INDICATOR.

1,325,131.

Specification of Letters Patent. Patented Dec. 16, 1919.

Application filed October 25, 1915. Serial No. 57,829.

To all whom it may concern:

Be it known that I, CHARLES W. WRIGHT, citizen of the United States, residing at Topeka, in the county of Shawnee and State of Kansas, have invented certain new and useful Improvements in Street and Station Indicators, of which the following is a specification.

This invention relates to improvements in electric automatic street and station indicators and is designed more particularly as an improvement upon that class of street and station indicators described and claimed in my copending application for Letters Patent, filed June 10th, 1915, Serial #33,362.

Essentially, the invention may be said to consist of manually operated indicator control mechanism; although provision has been made for automatic operation, if desired; of an electrically operated annunciator or indicator mechanism; and a suitable electrical connection therebetween.

The object of the invention is to provide a means whereby the names of various streets, stations, stops or localities may be successively displayed for view, interiorly of a street railway car or other public conveyance, that the occupants of such car, if desirous of alighting, may prepare therefor in ample time and with the assurance that the stop thereafter made is positively as indicated and hence correct.

A further object of the invention is to generally improve in the construction, combination and arrangement of parts constituting said control mechanism and said indicator; the nature of the mentioned improvements being hereinafter more particularly pointed out and specifically set forth in the appended claims.

In describing my invention in detail reference will be had to the accompanying drawings wherein like characters denote like or corresponding parts throughout the several views, and in which:

Figure 1 is a rear elevation of the street and station indicator mechanism;

Fig. 2 is a top plan view of said mechanism;

Fig. 3 is an elevation of the "loop" or "belt line" mechanism.

Fig. 4 is an end view of the mechanism illustrated in Fig. 3;

Fig. 5 is a detail plan view of a novel type of electrical switch device; 55

Fig. 6 is a side elevation of the device illustrated in Fig. 5;

Figs. 7, 8 and 9 illustrate a type of spool shaft;

Fig. 10 is an elevation of one of the spools or reels; 60

Fig. 11 is an elevation of the indicator control mechanism;

Fig. 12 is a section on the line 12—12 of Fig. 11; and 65

Fig. 13 is an elevation of a modification whereby operation of the indicator control mechanism may be rendered automatic.

Before proceeding with a description of the drawings I desire to call particular attention to the fact that while I have evolved my invention with reference to its use as a street and station indicator, the same, if desired, may be automatically controlled and consequently used as a means for displaying advertising matter, etc. 70

Referring now to the drawings by numerals, 1 designates as an entirety the annunciator or street indicator and 2 as an entirety the control means therefor, the former, the street or station indicator 1 being located conveniently within the car and in full view of the occupants thereof, and the latter, said control means, in such proximity to the motorman or car attendant as to be at all 75 times subjected to his manual control.

In its preferred embodiment, the street or station indicator 1 may be said to consist of an electric motor 3, the shaft 4 of which carries a gear 5 for meshing engagement 90 with a comparatively large gear 6 mounted on a shaft 7 journaled in bearings 8 therefor. Said shaft 7 in turn carries a gear 9 for meshing engagement with a gear 10 mounted on a shaft 11 journaled in bearings 95

12. Said shaft 11 is disposed in a plane below that of the shaft 7 and in parallelism therewith. A bevel gear 13 is mounted on shaft 11 for meshing engagement with a like gear 14 mounted on a shaft 15 journaled 100 in a suitable bearing 16 therefor. Said shaft 15 carries a bevel gear 17 for meshing engagement with a like gear 18 in turn mounted on a vertical shaft 19. A gear 20 is mounted on shaft 19. Rotation of said gear 105 20, through the intermediaries 21, 22 and 23,

will correspondingly rotate a gear 24 mounted on a vertical shaft 25. Said shaft 19 is equipped with a spool or reel 26 and shaft 25 with a spool or reel 27, said spools in 5 turn supporting a display sheet or tape with the street and station names thereon.

That the loop or belt line mechanism may be operated by motor 3, I mount a gear 29 on shaft 11, said gear being disposed for 10 meshing engagement with a like gear 30 mounted on a shaft 31 journaled in a suitable bearing 32. Shaft 31 carries a worm 33 for meshing engagement with a worm gear 34 mounted on a shaft 35 journaled in 15 bearings 36. Shaft 35 carries a gear 37 for meshing engagement with a comparatively large operating gear 38 mounted on a shaft 39. Bearings 40 support the shaft 39. A relatively large disk 41 is mounted on shaft 20 39 for rotation with gear 38.

Uniformly spaced circumferentially alined concavities or apertures 42 are formed adjacent the periphery of said disk 41 for the reception of a pin 43. An arm 44 is mounted 25 loosely upon shaft 39 for movement with said disk, the pin 43, by reason of its engagement with one of the apertures 42, affording a means whereby said arm 44 is locked to said disk in an adjusted position. 30 Arm 44 is enlarged at its free end as indicated at 45 to overlap and extend beyond the periphery of the disk 41. Movement of said arm in the path of a circle subsequent to adjustment, will bring said arm to the position illustrated in Fig. 3 whereby to forcibly abut and depress a vertically slidable switch arm 46. Said arm 46 is provided with a slot 47 through which a pin 48 rigid with a support 49 extends. Said arm 46 is pivoted 35 as at 50 to a switch lever 51 in turn pivoted as at 52 to the support 49 so that movement of said arm 46 will cause said lever to be moved into and out of engagement with co-operating stationary contacts 52; a spring 40 51^a being placed beneath the arm 46 to normally retain the lever 51 in such engagement. A stand 53 supports the switch mechanism just described.

A solenoid 54 is disposed directly beneath 50 the motor 3, the core 55 of which is fastened by any suitable means to a bodily movable cylinder or the like structure 56. Movement of structure 56 is against tension of a spring (not shown) inclosed therein. A 55 standard 57 acts as a support for the structure 56 and also as a support for a stationary contact element 58. The opposite end of the movable structure 56 from that attached to the core 55 of the solenoid has 60 fastened thereto as indicated at 59 an angle plate 60, the horizontal flat portion of which is provided with a slot 61 through which guide pins 62 extend. Angle plate 60 is mounted for sliding movement on a suitable 65 support 63.

A substantially U-shaped bracket 64 is fastened to the plate 60 as indicated at 65, the extensions of said U-shaped plate affording guides for a rod 66 which passes therethrough. Lugs 67 are hung to depend from a bridge plate 68 equipped with contact rollers 69. A spring 70 embraces the rod 66 to abut the respective lugs 67 and the respective extensions of the bracket 64 that said bridge plate 68 may be yieldingly maintained 75 against movement transversely of the plate 60.

Each of the rollers 69 is mounted to rest on an insulating strip 71 fastened to the support 63. A contact 72 is practically inclosed 80 by one of the insulating strips 71 and disposed preferably intermediate the ends of said strip and adjacent one of the longitudinal edges thereof that one of said rollers 69 may contact therewith when the plate 60 is 85 moved transversely of the support 63 through movement of the solenoid core 55 and the structure 56. Movement of the plate 60 in the manner stated will so move a contact 73 as to bring said contact into engaging proximity with the fixed contact 58 before mentioned.

Opposed trip devices 74 are pivoted as at 75 upon the top of the bridge plate 68. Movement of said bridge plate in the manner stated will position said trip devices directly beneath a disk 76 mounted on the shaft 11. A pin 77 extends beyond the periphery of the disk 76 to engage with the respective trip devices by rotation of the shaft 11. Said trip devices 74 being pivoted for movement in opposite directions, it is evident that the pin 77 will ride over one of said devices by rotation of the disk 76 and forcibly contact the other of said devices to laterally shift the plate 68 and in this manner remove one of the rollers 69 from engagement with its associate contact device 72. Such movement of the bridge plate 68 is against tension of the springs 70 105 hereinbefore described.

Coming now to a detail description of the spools 26 and 27, attention is directed to the fact that said spools are constructed in duplicate and that a description of but one will 115 therefore ensue.

Both the shaft 19 and the shaft 25 are made sectional, one section of each shaft being of a length equal to that of its associate spool. In the description following, the lower sections of the shaft 19 will be designated 19' and the lower section of the shaft 25, 25'.

A head 78 is formed on section 19' of the shaft 19, the mentioned head being provided with a transverse dovetailed groove 79 into which a complementary extension 80 of the head portion 81 is fitted that the two head portions 78 and 81 may be locked to move in synchronism. Head portion 81 is 125

made fast to the upper section of the shaft 19 that the spool 26 may be removed from the inclosing box or casing. Head 78 is equipped with a keeper bar 82 for coöperation with a latch bar 83 rigid with the head portion 81. Latch bar 83 is resilient that a lug 84 formed thereon may be withdrawn from a recess 85 therefor formed in keeper bar 82. When said lug 84 is in fitting engagement with said recess or notch 85, the head portions 78 and 81 cannot be relatively moved. A pin 86, formed on the head portion 78 to extend into the groove 79 thereof, is located for fitting engagement with a recess 87 formed in the enlargement 80 of the head portion 81 that movement of the respective head portions may be limited in assembling the sections of the shaft 19 and of shaft 25.

20 Guide rollers 90 facilitate movement of the tape 28. Somewhat elongated thumb screws 91 connect the respective spools 26 and 27 to the shafts 19 and 25.

Passing on to a description of the indicator control mechanism, 92 designates a horizontally movable contact element and 93 a vertically movable contact element, said two elements coöperating in the manner hereinafter more particularly described.

30 Vertically movable contact element 93 is normally maintained in its uppermost position through the medium of a spring 94 affixed thereto and to the casing 95 within which the control mechanism is arranged.

35 Said element 93 is laterally enlarged as indicated at 96, the enlarged portion being provided with a slot 97 through which a pin 98 extends, the mentioned pin affording a fastening means for an armature support 99 movable vertically with the element 93 and transversely independently thereof throughout the length of said slot 97. Armature support 99 has secured thereto as indicated at 100 a plate member 101 to which the 45 armature 102 is directly fastened. Electromagnetic devices 103 are disposed directly beneath the armature 102 that said armature may be held in engagement therewith when depressed and moved against action of spring 94.

Contact element 92 carries a guide bar 104 for the armature support 99. Said guide bar also provides a means whereby said support 99 is shifted relatively to the enlargement 96 by movement of said element.

55 Pawls 105 and 106 are pivoted respectively as at 107 and 108 to extensions 109 and 110 of the armature support 99 for co-operation with ratchet wheels 111 and 112. Ratchet 111 is mounted on a shaft 113 journaled in the control box 95. Said shaft carries a spool 114 and a gear 115, the latter having connection with a like gear 116 through intermediaries 117, 118 and 119. 65 Gear 116 is mounted on a shaft 120 parallel

with the shaft 113 aforesaid, said shaft mounting not only said gear 116, but a ratchet wheel 112 and a spool 122, the latter, coöperating with spool 114 in supporting the tape 123 for the indicator control 70 box or casing. Rollers 124 facilitate movement of the tape in the manner desired and position said tape for movement beneath a sight opening 125 formed in said box or casing. Pawls 105 and 106 are connected by a spring 126 that the mentioned pawls may be yieldingly maintained in engagement with the teeth of the respective ratchets. By shifting element 92 to the left, pawl 106 will contact with ratchet 112 and 75 by shifting said element 92 to the right, pawl 105 will contact with ratchet 111. Depression of contact 93 will cause the mentioned pawls to so engage the respective ratchets, (one or the other) as to rotate 80 either the shaft 120 or the shaft 113 and consequently wind or unwind the tape 123 as the case may be.

85 Gear 116 is in mesh with a comparatively large gear, this last mentioned gear being 90 mounted on a stub shaft 127 journaled in the casing 95 and a spring-motor casing 128. The spring motor (not shown) is mounted within said casing and is connected to said shaft 127 and to said gear 126 for a purpose hereinafter described. A stationary contact device 129 is positioned directly beneath contact element 93 and a stationary contact 130 directly in the path of movement of contact element 92.

95 A pawl 131 is pivoted as at 132 to the contact element 92 for engagement with the ratchet 112 that a reverse movement of the shaft 120 cannot take place through action of the spring (not shown) inclosed in the 105 motor casing 128. Said pawl 131 is yieldingly maintained in engagement with said ratchet by means of a spring 133 connected thereto and to said motor casing. Guides 134 support the contact element 92 for sliding movement.

100 Element 93 is equipped with a handle 135 that it may be manually depressed and element 92 with a handle 136 that it may be manually shifted or moved, said two handles 115 projecting exteriorly of the casing 95 as shown to advantage in Fig. 12. A thumb screw 137 is mounted on the motor shaft 127 that operation of the gear 126 may be subjected, if desired, to manual control.

120 A suitable motor reverse mechanism is directly associated with the contact element 92. An arm 138 fulcrumed as at 138' is pivoted as at 139 to said element 92. Said arm 138 is bifurcated as at 140 that a crank pin 125 141 forming a part of the motor reverse mechanism designated as an entirety by the numeral 142 may fit the mentioned bifurcation. A spring 143 is connected at one end to said pin 141 and at its opposite end to the 130

4
arm 138, the mentioned spring yieldingly maintaining said arm and said pin in proper operative relation.

Spools 114 and 122 are each recessed as indicated at 144 and provided with a longitudinally extending rod 145 that the terminals of the tape 123 which is connected to said spools may be fastened to the core of the mentioned spools with facility and ease.

10 The manner in which said spools are constructed is best illustrated in Fig. 10.

In Fig. 1 I have illustrated the preferred arrangement of the mechanism constituting the indicator proper, the spools 26 and 27 being mounted on a shelf 146 located in the box or casing containing the entire mechanism and the shelf in turn supported as indicated at 146^a, a support being at each side of the box or casing. Motor 3 is elevated as indicated in Fig. 1, a suitable motor stand supporting said motor in the position stated. A sign board 148 (electrically illuminated if desired) may be positioned interiorly of the box or casing containing the indicator mechanism and displayed for view to the occupants of the car or other public conveyance within which said indicator is arranged.

Before proceeding with a description of 30 the operation, I desire it to be understood that contacts 129 are in circuit with the solenoid 54 and with a suitable source of current supply (not shown). Contacts 58 and 73 are in circuit with the motor 3 and 35 with the current supply. Contacts 69 and 72 are in circuit with the electro-magnetic devices 103 and said current supply. Contacts 52' are in circuit with the motor reverse mechanism 142 and with said current 40 supply. Contacts 130 are in circuit with the solenoid 54 and said current supply. The current supply may be derived through any suitable source such as an overhead wire or underground rail, the indicator being preferably used upon electric street railway cars and other electrically operated public conveyances.

In describing the operation, I will assume that the indicator is mounted for operation 50 on an electrically propelled public conveyance such as a street railway car. Before starting a loop or belt line "run" the motorman or other attendant should set arm 44 as required and according to the number of 55 streets to be crossed *en route*. Before coming to each street (when manually operated) the motorman or other attendant should depress handle 135 and through such action move contact element 93 into engagement 60 with the contact devices 129 whereupon the electrical circuit within which solenoid 54 is arranged may be closed. Energization of the magnet 54 will cause structure 56 to be moved relatively to the support 57 and contact 65 73 brought into engagement with con-

tact 58. Movement of the contact 73 in the manner stated will cause the circuit within which the motor is arranged to be closed. Movement of structure 56 will also cause plate 60 to be moved relatively to its support, such movement bringing roller contact 69 into engagement with the contact 72. Movement of the last mentioned contact in the manner stated will cause magnet 103 to become energized and armature 102 to be held in engagement with said magnet so long as said magnet is in a state of energization. Rotation of the motor shaft 4 through the intermediaries previously outlined, will cause the spools 26 and 27 to be rotated in synchronism and the display sheet or tape wound thereon to be moved a predetermined distance before the sight opening (not shown) of the indicator box or casing. Operation of the motor will also cause the loop line mechanism to be operated, and, through the gearing indicated at 29, 30, 33 and 34, set in motion the gear 38 and consequently the disk 41 mounted to rotate with said gear. The gearing before mentioned is of such a nature as to cause the operating gear 38 to be moved but a fraction of a revolution and, upon each operation of the motor 3, cause the arm 44 to be moved farther away from the position indicated in Fig. 2.

Operation of the motor 3 will also set in motion the disk 76 mounted on shaft 11 and cause pin 77, extending from the periphery thereof, to contact with the trip devices 74. 100 As the said pin 77 engages with that particular trip device immovable in the direction in which the pin is moving the bridge plate 68 on which the trip device is mounted will be shifted laterally of the support 63 to thus break the electrical circuit of which the contact devices 69 and 72 form a part. By thus breaking this circuit, magnets 103 are deenergized, the armature 102 released, and the contact element 93 returned through action of spring 94, to its original position and out of engagement with the contact elements 129. Such return movement of the element 93 will cause the electrical circuit within which solenoid 54 is arranged to be 110 broken, such action permitting said solenoid to become deenergized and the plate 60, through action of the spring inclosed by structure 56, returned to its original position, as illustrated in Fig. 1. Action of this last mentioned spring (not shown) will cause the trip devices heretofore mentioned to be moved bodily out of the path of movement of the pin 77. This return movement of the structure 56 will also break the electrical circuit of which contacts 58 and 73 are a part, and as said contacts are in circuit with the motor, it is evident that the latter will be stopped. Through such operation, each individual depression of the handle 135 120

will cause the display sheet 28 to be moved only a predetermined degree or sufficiently to bring the name of the next succeeding street name into view through the sight 5 opening (not shown).

Depression of the element 93 will also cause pawl 106 to so act upon the ratchet wheel 112 as to cause the shaft 120 upon which said ratchet is mounted to be rotated 10 sufficiently to move tape 123 beneath the sight opening 125 a predetermined degree. Shaft 120 is connected to the shaft 113 as hereinbefore pointed out that the spools 122 and 114 may move in synchronism. Rotation of shaft 120 will cause gear 126 to be 15 rotated and the spring motor wound.

After determining the number of streets upon a loop line, arm 44 is revolved around dial 41 until it is positioned over the aperture corresponding to the number desired. 20 The dial and arm are then revolved back until the arm 44 is positioned directly over the switch lever 46, as shown in Fig. 3. Now each time handle 135 is depressed, the dial 25 41 and arm 44 are moved upwardly the distance between the two apertures. When the original terminal is reached, by means of handle 136, lever 92 is moved to the right so that it is in engagement with switch 130. 30 As soon as switch 130 is closed, the motor 3 will revolve in the opposite direction and the tape rewind. This will continue until the arm 44 reaches the position shown in Fig. 3, where it will depress lever 46 to stop 35 the motor. It will be obvious that as the motor rotates in the reverse direction, the arm 44 will be moved upward to permit the lever 51 to again engage the contact 52.

When the arm 92 is moved to the right to 40 bring the terminal thereof into engagement with contact 130, the pawl 131 will be disengaged from the ratchet 112 and the spring motor 128 will be released to thereby operate to rewind the tape 123 on the spool whereby 45 it may be intermittently unwound in the manner stated above when the car again traverses a loop line.

It is to be noted that the spools upon which the display tape is wound, in both 50 the indicating and control mechanism, are adapted to be releasably secured to their supporting stems through the medium of set screws or the like. In this manner the spool that is winding up must be fixed to its shaft, 55 and the unwinding spool released from its shaft by disengaging its set screw. This is true in regard to both the control and indicating devices. Thus, the winding roll of tape owing to its constantly increasing 60 diameter will be compensated for owing to the free unwinding movement of the unwinding spool relative to its supporting shaft thereby preventing any binding or strain upon the tape during winding or 65 unwinding thereof.

In the modification illustrated in Fig. 13, I have shown a means whereby contact element 93 of the indicator control mechanism may be depressed automatically and other than through manipulation of the handle 70 135. Said modification includes a track obstacle 150 positioned in proximity to one of the railway rails and provided with an inclined surface, said roller being disposed at one end of a vertically slidable rack bar 75 152. Said rack bar is provided with a longitudinally extending slot 153 through which guide pins 154 extend. The teeth of said rack 152 are in mesh with a gear 155. A second rack bar 156 is mounted to engage 80 with the gear 155 at a point diametrically opposite to that point engaged by the rack bar 152. The last mentioned rack bar 156 is fulcrumed as at 157, the fulcrum pin operating in a slot 158 formed in said rack 85 bar. The upper end of the rack bar 156 is extended at an angle as indicated at 159 and provided with an arcuate slot 160 through which a pin 161 extends. The mentioned pin projects laterally of the armature support 101. Upward movement of the rack bar 152 will cause gear 155 to be rotated and rack bar 156 to be depressed. Movement of the last mentioned rack bar 90 in the manner stated will cause the armature support 102 to be drawn into engagement with the electro-magnetic devices 103, such engagement permitting the circuit controlled through movement of element 93 to be closed and said magnet 103 energized as 95 hereinbefore pointed out.

That the automatic control device may be rendered inoperative, I provide a rod 162, one end of which is hooked as indicated at 163 to engage with the rack bar 156 that 100 said rack bar may be swung on its fulcrum 157 to disengage said gear. An enlargement 164 is formed on the bar 162 to contact with the indicator control box or casing that said bar 156 may be locked in 110 its withdrawn position if desired. A spring 165 is arranged to embrace said bar 162 and to abut respectively the rack bar 156 and the control box casing that the former may be normally maintained in the position illustrated in Fig. 13. A knob 166 is to be formed on one end of the rod 162 that manual manipulation of said rod may be rendered possible.

In reduction to practice, I have found 120 that the form of my invention, illustrated in the drawings and referred to in the above description, as the preferred embodiment, is the most efficient and practical; yet realizing that the conditions concurrent with the 125 adoption of my device will necessarily vary, I desire to emphasize the fact that various minor changes in details of construction, proportion and arrangement of parts may be resorted to, when required, without sac- 130

rificing any of the advantages of my invention, as defined in the appended claims.

Having thus fully described my invention, what I claim as new and desire to secure 5 by Letters Patent, is:—

1. In an indicator for common carriers, a display sheet, a first electrical circuit including therein a source of current supply and an electro-magnetic device, a second 10 electrical circuit including therein a motor and a source of current supply, a third electrical circuit including therein a source of current supply and an electro-magnetic device, a means movable to close the first circuit, means movable upon the energization of said first mentioned electro-magnetic device to close said second circuit, and said third circuit to energize the electro-magnetic device therein, said last-mentioned 15 electro-magnetic device operating automatically to hold the first mentioned circuit closing means against return movement, motor driven mechanism for moving the display sheet, and a means operated by the motor to break the third circuit, to deenergize the magnetic device therein, and release the circuit closing means to thereafter stop the motor subsequent to a predetermined movement of the display sheet, substantially as 20 described.
2. In an indicator for common carriers, a display sheet, a first electrical circuit including therein a source of current supply and an electro-magnetic device, a means to close said first circuit, a second electrical circuit including therein a source of current supply and a motor, a means to close said second circuit upon the energization of said magnetic device, a third electrical circuit 25 including therein an electro-magnetic device and a source of current supply, the electro-magnetic device in said third circuit operating to maintain the first circuit closing means in a circuit closing position, motor 30 driven mechanism for moving the display sheet, and a means operating automatically

to break the third circuit subsequent to a predetermined movement of the display sheet, substantially as described.

3. In an indicator for common carriers, 50 a display sheet, a first electrical circuit including therein an electro-magnetic device and a source of current supply, a spring pressed member movable against tension of its associate spring upon energization of 55 said electro-magnetic device, a second electrical circuit including therein a motor and a source of current supply, said second circuit being opened and closed through movement of said member, motor driven mechanism 60 for moving said display sheet, a third electrical circuit including therein an electro-magnetic device and a source of current supply, said third electrical circuit being closed through movement of said member, 65 means to be engaged by the electro-magnetic device of said third electrical circuit to retain said first circuit closed, and means driven by said motor to break the third circuit, substantially as described. 70

4. In a street and station indicator for common carriers, a display sheet, mechanism including a motor operable to move said display sheet in one direction, an electrical circuit including therein a motor reverse mechanism and a source of current supply, a rotatable disk, a means rotating said disk through operation of said motor, an arm adjustable relatively to said disk, means to lock said arm against movement 80 subsequent to adjustment, and a means disposed in the path of movement of said arm to be engaged thereby when said display sheet shall have reached its limit of movement to break said electrical circuit for the 85 purpose specified. 75

In testimony whereof I affix my signature in presence of two witnesses.

CHARLES W. WRIGHT.
